UNITED STATES PATENT OFFICE.

CHARLES ZALLUD, OF NEW YORK, N. Y., ASSIGNOR, BY MESNE ASSIGNMENTS, TO R. HOE AND CO., OF NEW YORK, N. Y., A CORPORATION OF NEW YORK.

DELIVERY MECHANISM FOR PRINTING-MACHINES.

1,087,206.

Specification of Letters Patent. Patented Feb. 17, 1914.

Application filed July 16, 1908. Serial No. 443,765.

To all whom it may concern:

Be it known that I, CHARLES ZALLUD, a citizen of the United States, residing at New York, county of New York, and State 5 of New York, have invented certain new and useful Improvements in Delivery Mechanisms for Printing-Machines, fully described and represented in the following specification and the accompanying drawings, forming a part of the same.

This invention relates to certain improvements in delivery mechanism for printing machines.

Where the product of printing machines 15 comprises heavily printed sheets, such as illustration work or other work requiring a considerable body of ink, especial care has to be taken to prevent smutting or offsetting as the product is delivered.

The object of this invention is to produce an improved delivery mechanism which is adapted for use with printing machines where the product is of such a character 20 that there is liability of smutting or offsetting the product as it is delivered.

With this and other objects in view, the invention consists in certain constructions, and in certain parts, improvements and combinations as will be hereinafter fully described and then specifically pointed out in 25 the claims.

Referring to the accompanying drawings Figure 1 is an end elevation, partly in section, of one form of delivery mechanism of 35 printing machines embodying the invention. Fig. 2 is a sectional elevation of the construction illustrated in Fig. 1. Fig. 3 is a detail view.

Referring to the drawings which illustrate one embodiment of the invention, 40 1 illustrates the side frames of the machine in which the several parts hereinafter referred to are mounted.

Machines embodying the invention will 45 employ a suitable delivering means which may be widely varied in its construction. In the particular machine illustrated, the delivering means includes a rotating carrier comprising a pair of disks 3 mounted on a shaft 2, this shaft being the main shaft of the delivery mechanism. The shaft may be driven in any suitable manner, as from a gear 4 which may be in mesh with a suitable driving gearing deriving its motion from the printing machine. Operating in con-

nection with the disks 3 in the particular machine shown is a pair of grippers 5, these grippers operating in connection with a pair of abutments 6 carried on the disks 3. These grippers 5 may be operated in any ordinary manner. In the construction shown, they are shown as mounted on a shaft 7, supported in the disks 3, the shaft being provided with a rock-arm which carries a roll 8 which runs on an opening cam 60 9, the grippers being held closed by the ordinary spring rod construction, indicated at 10. The sheets may be forwarded to the delivering grippers, when this form of delivery means is employed, in any suitable 65 manner. As shown, the sheets are tucked between a pair of rolls 11 by a blade 12 and are led to the grippers by means of a pair of ordinary sheet guides 13.

The delivering mechanism, whatever be the form employed, will operate to transfer the sheets to suitable sheet receiving mechanism. This sheet receiving mechanism may be widely varied in its construction. In the best constructions, and as shown, a plurality 70 of sheet receivers will be employed, each of which receivers will be made up of a plurality of coöperating parts, these parts being independently supported and manipulated in such a way that they will be 75 brought into proper position with respect to each other when they reach the sheet receiving position. These receivers will, further, be moved from the sheet receiving 80 to the sheet delivering position, the movement of each receiver from the receiving to the delivering position being a parallel 85 movement.

In the particular machine illustrated, a plurality of sheet receivers is employed, each 90 of these receivers consisting of a pair of sheet supports, each support consisting of a bar 14 mounted on fingers 15, these fingers being in turn carried on rods 16. These sheet supports are, in the particular construction illustrated, mounted on carriers which are oppositely disposed and the construction of which may be widely varied. As shown, each carrier is a traveling carrier 95 and comprises a pair of chains 17, these chains running around upper sprockets 18 and lower sprockets 19. The sprockets 18 are supported on a shaft 20 mounted in brackets 21 and the sprockets 19 mounted on shafts 22 which are supported in bear- 100 105 110 115

ings 23. These bearings are carried on rods 24 which extend through sleeves 25 on brackets 26, this construction providing for adjustment on the shafts 22 so as to overcome any slack in the chains.

In the particular machine illustrated, the sheet supports operate to support the sheets on the sides only, thereby avoiding as far as possible contact between the sheets and the sheet supports. With a construction such as described in which the sheet supports operate to carry the sheets on the sides only, there is liability that the sheets being unsupported at their centers will sag. The supports will, therefore, in the best constructions be so constructed as to prevent this sagging. While this may be done in various ways, it may be effectively accomplished by so constructing the supports as to bend the sheets out of line at the sides, this bending of the sheets at the sides serving to stiffen them. In the particular construction illustrated, the bending of the sheets is effected by concaving the bars slightly, as clearly illustrated in Fig. 3, so that when the sheets are deposited thereon they will be bent up at their sides.

The sheet receiver or receivers, if more than one be employed, will be intermittently moved from the sheet receiving to the sheet delivering position. The means by which this intermittent movement is accomplished may be of any suitable character. In the particular construction illustrated, the shafts 20 which carry the upper sprockets are provided with miter gears 27 in mesh with similar gears 28 on a shaft 29 suitably supported in the frame. The shaft 29 is provided with a gear 30 which is one of a train of gears indicated at 31, which train may be operated from a ratchet wheel 32 supported on a stud 33 extending from the frame. This ratchet wheel may be operated by any suitable pawl mechanism, not illustrated, construction of this character being well understood in the art. In the best constructions, however, this movement will be such as to give the sprockets a quarter turn so that the sheet supports on the oppositely disposed carriers will be brought into sheet receiving position, thus avoiding any movement of the sheet supports with respect to the sheets after the sheets have been placed thereupon.

While the sheets might be removed from the sheet receivers in various ways, in the best constructions including the invention, pile delivery mechanism will be employed. This pile delivering mechanism may be variously constructed but in the particular machine shown it includes a conveyer consisting of a series of chains 34 which are supported by sprockets 35, 36, these sprockets being supported on shafts 37, 38. The conveyer chains, if desired, may be provided with spacing projections, indicated at 39. The

conveyer will, in the best constructions, be located in the path of the sheet receivers and between the inner ends of the sheet receivers, as is clearly shown in Fig. 1, and, further, will be such a distance from the receiving position of the receivers, that as the receiver carriers are given the quarter turn referred to, the ends of the sheet supports will pass the sides of the conveyer, thus depositing the pile of sheets thereon. It will be observed that at the time the receivers are moving from receiving to delivering position the movement is a parallel one, so that the sheets are deposited on the conveyer without displacing the sheets.

If desired, supports, as 40, may be provided on each side of the conveyer, which supports will when employed, be so arranged as to bear only on the margins of the sheets, thus preventing the sheets from bending downward and at the same time not smudging the sheets. These supports may be made of polished steel bars. In the particular construction illustrated, they are carried by brackets 41 supported on cross rods 42. The conveyer chains, to prevent sagging, may be provided at suitable distances apart with rolls 43 which run on supporting tracks 44 carried on the cross rods 42 before referred to.

The conveyer, when it is employed, may be operated in any suitable manner. In the construction illustrated, the shaft 38 is a driven shaft and is given a step by step movement by a ratchet wheel 45 and a pawl 46, this pawl being worked through connections 47 of the usual type from a cam or eccentric on the shaft 2.

To prevent overthrow of the sheets, as they are delivered by the delivering cylinder, there may be employed, if desired, sheet stops 48 so located that the forward edge of the sheet will strike them as they are released by the grippers 5, the sheets being thus caused to settle evenly on the sheet receivers.

Changes and variations may be made in the constructions by which the invention is carried into effect. The invention is not, therefore, to be limited to the specific construction herein described and illustrated in the accompanying drawings.

What is claimed is:—

1. The combination with a plurality of sheet receivers which are successively brought into receiving position, of means for giving the receivers a movement after a plurality of sheets have been placed upon one of them to carry a filled receiver and the sheets thereon flatwise and to bring an empty receiver into receiving position, a pile delivery mechanism in the path of the filled receiver to which it delivers the sheets, and means for positively delivering the sheets flatwise to the sheet receivers.

2. The combination with a plurality of sheet receivers which are successively brought into receiving position, of means for giving the receivers a movement after a plurality of sheets have been placed upon one of them to carry a filled receiver and the sheets thereon flatwise and to bring an empty receiver into receiving position, means for positively delivering the sheets flatwise to the sheet receivers, a conveyer in the path of the filled receiver to which it delivers the sheets, and means for operating the conveyer to forward the pile of sheets edgewise.
3. The combination with sheet delivering means, of a sheet receiver comprising a plurality of sheet supports, carriers on which the supports are mounted, and means for operating the carriers to bring the component sheet supports of each receiver into line with each other in position for receiving the sheets and delivering them, the movement of the supports from receiving to delivering positions being a parallel movement.
4. The combination with sheet delivering means, of a plurality of oppositely arranged traveling carriers, a plurality of sheet supports similarly arranged on the carriers, the sheet supports on one carrier coöperating with the sheet supports on the other carrier to form sheet receivers, means for operating the carriers to move the sheet supports successively into line with each other and from sheet receiving to sheet delivering positions, and a pile delivery mechanism to which said receivers deliver.
5. The combination with sheet delivering means, of a plurality of oppositely arranged traveling carriers, a plurality of sheet supports similarly arranged on the carriers, the sheet supports on one carrier coöperating with the sheet supports on the other carrier to form sheet receivers; means for operating
- the carriers to move the sheet supports successively into line with each other and from sheet receiving to sheet delivering positions, a conveyer to which said receivers deliver, and means for operating the conveyer to forward the pile of sheets edgewise.
6. The combination with sheet delivering means, of a plurality of oppositely disposed traveling carriers, a plurality of sheet supports similarly arranged on the carriers, the sheet supports on one carrier coöperating with the sheet supports on the other carrier to form sheet receivers, a conveyer in the path of movement of the supports, and means for operating the carriers to move the supports into line with each other in sheet receiving position and to the conveyer, the movement of the supports from the receiving position to the conveyer being a parallel movement.
7. The combination with sheet delivering means, of a plurality of sheet receivers operating to support the sheets at the sides only, each sheet receiver being made up of a plurality of sheet supports, the operating surfaces of the supports being constructed to bend the sheets out of line, and means for bringing the receivers successively into cooperation with the sheet delivery means.
8. The combination with sheet delivering means, of a plurality of sheet receivers, each receiver comprising a plurality of independent sheet supports constructed to bend the sides of the sheets out of line, and means for bringing the supports forming each receiver successively into receiving position.

In testimony whereof, I have hereunto set my hand, in the presence of two subscribing witnesses.

CHARLES ZALLUD
